UNITED STATES PATENT OFFICE.

WOOTEN L. BAUMANN, OF COALINGA, CALIFORNIA.

PAWL-AND-RATCHET DEVICE.

1,111,125.

Specification of Letters Patent. Patented Sept. 22, 1914.

Application filed March 14, 1914. Serial No. 824,742.

To all whom it may concern:

Be it known that I, WOOTEN L. BAUMANN, a citizen of the United States, residing at Coalinga, in the county of Fresno and State of California, have invented a new and useful Pawl-and-Ratchet Device, of which the following is a specification.

The present invention appertains to a flue expanding device, and relates more particularly to an actuating mechanism for flue expanders.

It is the object of the present invention to provide an appliance of the nature indicated, for actuating a common roller flue expander, in either direction, and for enabling the expander to be driven into the flue, without impairing or injuring the actuating mechanism due to the shocks.

The present invention also comprehends the provision of an appliance of the character specified, which will be comparatively simple, compact and inexpensive in construction, as well as being simple, convenient, substantial, serviceable and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:

Figure 1 is a longitudinal section of the improved appliance, portions being broken away. Fig. 2 is a cross section of the device, taken on the line 2-2 of Fig. 1.

In carrying out the present invention, there is provided a spindle or pin 1, having the tapered mandrel portion 2 at one end, and upon which an ordinary roller flue expander may be mounted. Various flue expanders may be employed upon the mandrel 2, and for this reason a detailed illustration and description thereof is not deemed necessary to an understanding of the present appliance. The mandrel 2 is provided with a retaining nut 3 at its free end, which is removable to permit the expander to be applied and removed. The shaft or spindle

1 is preferably provided with a retaining collar 4 at its other or outer end.

The body portion of the spindle or shaft 1 is provided with longitudinal feathers or splines 5, and collars 6 are mounted upon the spindle or pin 1 and seat against the ends of the feathers 5, the collars 6 being preferably locked in place by means of cotter pins 7 or the like.

A ratchet wheel 8 having square teeth is slidably mounted upon the body portion of the spindle or pin 1, and engages the feathers 5 in order that the spindle and ratchet wheel may be restrained from rotating with respect to one another, although the ratchet wheel and spindle may reciprocate or slide relative to one another. The ratchet wheel 8 is provided at its sides with bosses 9, and coiled wire compression springs 10 surrounding the spindle 1, are seated between the collars 6 and the bosses 9 of the ratchet wheel to yieldingly hold the ratchet wheel intermediate the collars 6.

The means for rotating the ratchet wheel 8 embodies an annulus or annular body 11 encircling the ratchet wheel 8, the opening 12 of the body 11 receiving the ratchet wheel loosely and annular plates or flat rings 13 being secured to the sides or faces of the body 11 by means of screws or other securing members 14, and loosely embracing the bosses 9 of the ratchet wheel. The inner edge portions of the retaining plates or rings 13 project beyond the edges of the opening 12 of the body, and overlap the faces or sides of the ratchet wheel, to retain the ratchet wheel within the body 11, and to permit the ratchet wheel and body to rotate with respect to one another. The periphery of the ratchet wheel 8 being confined or housed within the body 11 and retaining plates 13, will cause the body and ratchet wheel to shift longitudinally as a unit.

The body or annulus 11 is provided with a radial extension or boss 15, and a radial bore 16 extends through the projection 15 to the opening 12 of the body. Mounted within the bore 16 is a pawl or dog 17, of circular cross section, the same being disposed slidably and rotatably within the bore 16, and having an outwardly projecting stem 18 slidably through a ring or collar 19 threaded or otherwise engaged into the mouth of the bore 16. The stem 18 is provided with a handle or finger piece 20 at its

outer extremity, and a coiled wire compression spring 21 surrounds the stem 18 within the bore 16 and has its terminals seated against the collar 19 and the pawl or dog 17, and yieldingly presses the pawl or dog inwardly against the periphery of the ratchet wheel. The inner end of the pawl 17 is inclined or beveled, as at 22, and one side is flattened, as at 23, to present a beveled tooth for engaging the teeth of the ratchet wheel. The shoulder or flat side 23 of the pawl or dog is arranged to engage the teeth of the ratchet wheel, to turn the ratchet wheel with the body 11, while the beveled face 22 of the pawl or dog, is arranged to force the pawl or dog outwardly against the tension of the spring 21, when the body 11 is swung properly, with respect to the ratchet wheel.

20 As a means for rotating or oscillating the body 11, the same is provided with a radial socketed projection 24, adjacent the projection or boss 15, and threadedly receiving the inner end of a handle or lever 25, which may be of any suitable length according to the purchase desired upon the spindle or shaft 1.

The several component parts of the apparatus may be readily assembled as will be obvious from the foregoing, taken in connection with the drawing, and may also be readily taken apart for the purpose of cleaning, repair or replacement. The roller flue expander (not shown) may be readily applied upon the mandrel 2, when the retaining nut 3 is removed, in order that the expander may be driven into the flue or tube, with the mandrel 2, the body and outer end portion of the spindle or pin 1 projecting from the end of the flue. Attention is directed to the fact, that as the spindle or pin 1 is being driven, the springs 10 will permit the ratchet wheel and parts carried thereby, to yield in either direction, to avoid jars upon the ratchet wheel and parts carried thereby, inasmuch as the springs 10 tend to absorb the shocks.

The spindle or pin 1 may be forcibly rotated, to rotate the flue expander when desired by oscillating the handle or lever 25, which will cause the pawl or dog 17 to al-

ternately grip and ride idly back over the ratchet wheel, in order that the handle or lever 25 will impart an intermittent rotary movement to the spindle or pin 1. When 55 the pawl or dog 17 is arranged as illustrated in Fig. 2, the oscillation of the handle or lever will cause the ratchet wheel to be rotated in a counter clockwise direction, and if it is desired to rotate the ratchet wheel 60 and spindle in a clockwise direction, this may be readily accomplished by pulling the pawl 17 out of engagement with the ratchet wheel through the medium of the hand piece 20, and then turning the pawl through 65 an angle of 180 degrees so as to reverse the beveled face 22 and shoulder 23 of the pawl.

It will thus be obvious from the foregoing, taken in connection with the drawing, that the present appliance may be conveniently 70 and efficiently employed for both driving and rotating a flue expander, the present appliance being of advantage in several respects, as will be apparent from the foregoing without further comment. 75

Having thus described the invention, what is claimed as new is:—

1. In a device of the character described, a spindle, a ratchet wheel feathered thereon, shock springs mounted upon the spindle and 80 holding the ratchet wheel therebetween, a body rotatably mounted upon the ratchet wheel, and a pawl carried by the body and coöperable with the ratchet wheel.

2. In a device of the character described, 85 a spindle having a feather at one portion, collars mounted upon the spindle at the ends of the feather, a ratchet wheel slidable upon the spindle between the collars and engaging the feather, springs disposed between the ratchet wheel and collars, a body rotatably mounted upon the ratchet wheel, and a pawl carried by the body and coöperable with the ratchet wheel. 90

In testimony that I claim the foregoing as 95 my own, I have hereto affixed my signature in the presence of two witnesses.

WOOTEN L. BAUMANN.
